GAME BOARD AND GAME PIECES

Bing W. Hum, Washington, D. C.

Application April 14, 1952, Serial No. 282,194

3 Claims. (Cl. 273—131)

This invention relates in general to amusement devices, and more particularly to game apparatus including a game board on which game pieces are moved in playing a game.

The primary object of this invention is to provide an improved and novel game apparatus in which game pieces are employed and may be captured whereby players will exercise their ingenuity in moving game pieces in order to capture game pieces of an opponent.

Another object of this invention is to provide an improved game board which has the general outline of the flag of Korea, said game board being adapted to be utilized in combination with game pieces which may be captured, the playing of a game calling attention to the present world situation and developing a competitive spirit among the players.

Another object of this invention is to provide an improved game board which is divided into sectors with each sector being associated with indicia printed upon the game board for indicating the initial arrangement of the game pieces to be disposed thereon, said indicia also indicating the exact arrangement of game pieces required for the capturing of an opponent's game piece.

A further object of this invention is to provide an improved set of game pieces, said game pieces being of different configurations with the configurations on opposite faces of individual game pieces being identical, but having a reversal of color.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application in which:

Figure 1 is a top plan view of the improved game board, which is the subject of this invention, and shows the configuration thereof;

Figure 2 is a perspective view of one type of game piece tentatively used with the game board of Figure 1;

Figure 3 is a perspective view of another type of game piece intended to be utilized with the game board of Figure 1, said game piece also being adapted to be utilized in combination with game pieces of the type illustrated in Figure 2;

Figures 4, 6 and 8 are fragmentary diagrammatic views on a reduced scale of portions of the game board of Figure 1 and having game pieces disposed thereon, the view showing the various types of moves whereby the game pieces may be moved into capturing positions, the game board being slightly rotated in order to more clearly illustrate the arrangement of the game pieces; and

Figures 5, 7 and 9 are fragmentary diagrammatic views similar to the views of Figures 4, 6 and 8, respectively, and differing therefrom only in that the captured game pieces have been turned over and become game pieces of the capturing player.

Similar characters of reference designate similar or

2

identical elements and portions throughout the specification and throughout the different views of the drawings.

Referring now to the drawings in detail, it will be seen that there is illustrated in Figure 1 a game board 10, which is a major element of the game apparatus of this invention, the game board being in the form of a flat sheet of material. Outlined on the game board 10 is a playing surface 12 which has generally a regular octagonal outline. The playing surface 12 includes a central space 14 which is of the same outline as the playing surface 12 and concentric therewith. Extending outwardly and radially from the central space 14 are a plurality of sectors 16; there being one sector for each side of the playing surface 12. It will be noted that the playing surface 12 has the general outline of a portion of the flag of Korea and in order to call particular attention to the world situation and further interest in the game to be played on the game board, the playing surface 12 is divided in half by a diametrically extending line 18 which extends between diametrically opposite corners of the playing surface 12, the line 18 being designated by indicia 20 to indicate the same as being the 38th parallel.

In order that the playing surface 12 may be utilized in the playing of a game, each sector 16 is divided into a plurality of playing spaces 22 which extend in rows both axially from the central space 14 and circumferentially concentric with the central space 14. The central space 14 is provided with a plurality of intersecting radially extending indicating marks 24 for indicating the movement of game pieces from adjacent playing spaces 22 into the central space 14. The game board 10 is also provided with indicia 26 representing certain arrangement of game pieces and indicating the manner in which they are to be initially placed upon the playing surface 12. It will be understood that the indicia 26 for each sector 16 is different from that of the other sectors 16 and that the indicia may be utilized to indicate the arrangement of game pieces necessary for the capture of an opponent's game piece.

Referring now to Figure 2 in particular, it will be seen that there is illustrated one type of game piece, the piece being referred to in general by the reference numeral 28. The game piece 28 is flat and rectangular in outline so as to provide opposite faces 30 and 32. The face 30 is provided with a narrow transversely extending light strip 34 on a dark field which forms a major portion of the face 30. The face 32 is of the same configuration with the exception that the central narrow strip 36 extending transversely thereof and in vertical alignment with the narrow strip 34 is dark and is on a light field which forms a major portion of the face 32. It will be seen that by merely turning the game piece 28 over, the game piece may be transferred from one opponent to the other.

Referring now to Figure 3 in particular, it will be seen that there is illustrated a game piece 38 which has the same general outline as the game piece 28 and includes upper and lower faces 40 and 42, respectively. The faces 40 and 42 are of a solid configuration with the upper face 40 being dark and the lower face 42 being light. It will be seen that the game piece 38 can be transferred from one opponent to another by turning it over in the manner indicated above with respect to the game piece 28.

While the game board of Figure 1 has not been illustrated with the game piece 28 and 38 placed thereon, it will be understood that initially each of two opponents are provided with six of each type of game piece. The game pieces are positioned on the game board 10 on the outer three playing spaces 22 of the sector 16 in the order indicated by the indicia 26 disposed adjacent the respective

sectors 16. When the game pieces 28 and 38 are initially positioned upon the playing surface 12, one opponent will place his game pieces with the light side up and the opponent will place his game pieces with the dark side up.

The object of a game played with the game apparatus of this invention is to capture all of an opponent's game pieces. Inasmuch as each of the game pieces 28 and 38 have the same value and capturing power, it will be obvious that an opponent will hesitate to sacrifice a single game piece. When a game piece is captured, it is merely turned over so that its other face is up and it becomes a game piece of the capturing player.

Although the rules of a game played with the game apparatus of this invention may be varied, it has been found that the most interesting manner of utilizing the game apparatus is to require that three game pieces be aligned, either radially or circumferentially in order to capture an opponent's game piece. Furthermore, the game is made more interesting by permitting the capture of an opponent's game piece only when the three aligned game pieces are in the order indicated by the indicia 26 of the capturing player's sectors.

Referring now to Figures 4, 6 and 8, it will be seen that there are indicated various arrangements of game pieces and of the various manners in which the game pieces may be captured as clearly illustrated. For example, in Figure 4 the opponent having the dark game pieces has moved a game piece 28 into radial alignment with a game piece 38 of his own and a game piece 38 of his opponent. It will be noted that the movement of the game piece 28 is indicated by a dotted line in order to clearly illustrate the move made. The arrangement of the three game pieces is identical with that indicated by indicia 26 on the particular player's starting half of the game board 10 and is therefore a permissible arrangement of game pieces for a capture by the player having the dark game pieces. If the player having the light game pieces had moved his game pieces into the same arrangement, a capture would not be allowed inasmuch as he does not have that particular arrangement indicated on his half of the game board 10.

After the capture of the light game piece 38 has been realized, the capture is completed by turning the game piece over. As is best illustrated in Figure 5, the turning over of the light game piece 38 results in it becoming a dark game piece 38 and becoming one of the player's having dark game pieces.

Referring now to Figure 6, it will be seen that an opponent's game piece may also be captured by aligning three game pieces circumferentially. The figure also illustrates that the position of the captured game piece with respect to the capturing game pieces is immaterial with the exception that there must be only three game pieces in alignment in the line of capture. It will be noted that the player with the dark pieces has a dark game piece 38 positioned adjacent a light game piece 38 and that the player having the light game pieces has moved a second light game piece 38 into a playing space 22 adjacent the dark game piece 38 with the result that three game pieces are in circumferential alignment.

Inasmuch as the arrangement of game pieces in circumferential alignment is similar to that of one of the indicia 26 on the half of the game board 10 initially occupied by the player having light game pieces, the capture of the dark game piece 38 is permissible. As best illustrated in Figure 7, when the capture of the dark game piece 38 is realized, it is turned over and becomes a light game piece 38.

While the game pieces may be moved only one playing space 22 at a time, there is a possibility of capturing two of the opponent's game pieces at the same time. It will be understood that a game piece disposed within the central space 14 may be combined with the game pieces on opposite sides thereof to have three game pieces in axial alignment. It will be noted that the player having the dark game pieces has a dark game piece 38 in diametrically opposed relation to a light game piece 38 on opposite

sides of the central space 14. The same player also has a dark game piece 28 diametrically opposite a light game piece 28 with the central space 14 therebetween. Initially positioned in a playing space 22 was a dark game piece 28. As indicated by the dotted line, the dark game piece 28 was moved into the central space 14 with the result that the player with the dark game pieces now has two of his game pieces in axial alignment with one of the opponent's game pieces along two diametrically extending lines. It will be noted that the dark game pieces 38 and 28 are aligned with the light game pieces, and, this being one of the capturing arrangements for the player with the dark game pieces, the light game piece 38 is captured. Also, inasmuch as the arrangement of the three game pieces 28 is a capturing arrangement for the player having the dark game pieces, the light game piece 28 is also captured.

Referring now to Figure 9, it is seen that once the capture of the game pieces 28 and 38 have been realized, they are turned over and become dark game pieces. Inasmuch as there are eight sectors 16 there is a possibility of one player capturing simultaneously four of his opponent's game pieces.

Referring once again to Figure 8, it will be seen that the player having the light game pieces has two of his game pieces circumferentially aligned as one of the dark game pieces and ordinarily would be able to cancel the game piece 38. However the arrangement illustrated is not one of the capturing combinations of the player having white game pieces and therefore he is not permitted to capture the dark game piece 38.

While the manner of utilizing the game apparatus of this invention outlined above is the preferred method of playing the game, it will be understood that a more simple game may be played by disregarding the indicia 26 and permitting the capture of an opponent's game piece, regardless of the aligned combination, by merely aligning three game pieces, two of your game pieces and one of the opponent's. However, it is understood that capture is only permissible when the number of the game pieces aligned are limited to three.

The operation of this device will be understood from the foregoing description of the details thereof, taken in connection with the above recited objects and the drawings. Further description would appear to be unnecessary.

Minor modifications of the device, varying in minor details from the embodiment of the device illustrated and described here, may be resorted to without departure from the spirit and scope of this invention, as defined in the appended claims.

Having described the invention, what is claimed as new is:

1. In a game apparatus, a game board having a geometrical figure represented on the face of the board, said geometrical figure including a central space having the same outline as the geometrical figure, a plurality of sectors extending radially from the central space, each of said sectors being transversely divided to form a plurality of parallel playing spaces of progressively increasing width, said geometrical figure having the outline of a regular octagon, there being one sector for each side of said octagon, indicia on the face of the board adjacent each sector for indicating the initial positions of game pieces on said game board, game pieces having surface ornamentations of patterns identical with the patterns of the indicia on the game board.

2. In a game apparatus, a game board having a geometrical figure represented on the face of the board, said geometrical figure including a central space having the same outline as the geometrical figure, a plurality of sectors extending radially from the central space, each of said sectors being transversely divided to form a plurality of parallel playing spaces of progressively increasing width, said geometrical figure having the outline of a regular octagon, there being one sector for each side of

said octagon, indicia on the face of the board adjacent each sector for indicating the initial positions of game pieces on said game board, game pieces having surface ornamentations of patterns identical with the patterns of the indicia on the game board, said surface ornamentation being colored, said game pieces being flat and rectangular in outline with each having opposite faces with identical surface ornamentations but with reversal colors whereby said game pieces may be easily transferred between players when captured.

3. In a game apparatus, a game board having a geometrical figure represented on the face of the board, said geometrical figure including a central space having the same outline as the geometrical figure, a plurality of sectors extending radially from the central space, each of said sectors being transversely divided to form a plurality of parallel playing spaces of progressively increasing width, said geometrical figure having the outline of a regular octagon, there being one sector for each side of said octagon, indicia on the face of the board adjacent each sector for indicating the initial positions of game pieces on said game board, game pieces having surface ornamentations of patterns identical with the patterns of the indicia on the game board, the indicia for each sector

being different from the indicia of the other sector, said geometrical figure being divided by a line extending through a pair of diametrically opposed corners to form home playing areas for each of two opponents, the indicia identifying the sectors of a home playing area indicating the permissible capturing arrangement of game pieces by the opponent controlling such home playing area, the indicia identifying the sectors of one home playing area being different from the indicia of the other playing area whereby the two opponents have different capturing arrangements.
